UNITED STATES PATENT OFFICE.

ALGERNON S. SPAULDING, OF WORCESTER, MASSACHUSETTS, ASSIGNOR TO THOMAS & COMPANY, INC., A CORPORATION OF MASSACHUSETTS.

SANDING-MACHINE.

1,142,063.

Specification of Letters Patent.

Patented June 8, 1915.

Application filed February 26, 1915. Serial No. 10,853.

To all whom it may concern:

Be it known that I, ALGERNON S. SPAULDING, a citizen of the United States, residing at Worcester, in the county of Worcester and 5 State of Massachusetts, have invented a new and useful Sanding-Machine, of which the following is a specification.

This invention relates to a sanding machine for the purpose of sand-papering flat 10 surfaces particularly, although capable of other uses.

The principal objects of the invention are to provide a simplified machine for this purpose in which the article to be sand-papered 15 can be moved along a work-rest or support conveniently arranged, and will be accurately and uniformly sanded; to provide a construction in which only a portion of the surface of the sanding wheel can project 20 through the work-rest into a position to engage the work; to provide for adjusting the work-rest so as to get a higher or lower surface speed of the sanding wheel to operate upon it; and to provide other features of 25 construction as will appear hereinafter.

Reference is to be had to the accompanying drawings in which,

Figure 1 is a front elevation of a machine constructed in accordance with this invention; Fig. 2 is an end elevation; Fig. 3 is a central sectional view on the line 3—3 of Fig. 1; Fig. 4 is a horizontal sectional view on the line 4—4 of Fig. 1; Fig. 5 is an enlarged sectional view of the edge of the 35 sanding wheel; and Fig. 6 is an enlarged central sectional view of the support and adjusting device for one end of the sanding wheel shaft.

The machine is shown as comprising a 40 frame 10 having bearings for the horizontal sanding wheel shaft 11. This shaft is shown as provided with the usual tight and loose pulleys for the reception of a driving belt. On the front of the frame 10 is a wall or 45 plate 12 through which the shaft passes. This is provided with end walls 13. This constitutes a casing for the conical sanding wheel 14. This wheel is fixed on the end of the shaft 11 and is made of a comparatively 50 flat conical shape on its operative surface. This surface is provided with a layer of felt 15 and with a sheet of sand-paper 16 over the same. This is held at the center by a nut and washer 17 and at the edge by a band 18

surrounding the cylindrical edge of the 55 wheel.

At the front of the end pieces 13 is arranged a removable front plate 20 designed to be held against the ends 13 by hooks 21 or the like. At the top of this is a shelf 22 60 which has a portion 23 projecting inside each end piece 13. This member is fixed to an inclined flat work-rest 24 located above the front plate 20. This is held to the projection 23 on both sides by pins 25 passing 65 into the same through the end pieces 13 and it is secured to these end pieces at the top by similar pins 26. This work-rest is designed to receive the work against its front surface and is inclined at the same degree as 70 the conical surface of the wheel is inclined from a plane at right-angles to the shaft. In other words, it is substantially tangential to the conical surface of the wheel. It is provided with a segmental opening 27 there- 75 through which receives the wheel and allows a portion of the wheel to project through it. This opening is arranged with its center co-incident with an element of the conical surface of the wheel, and thus permits this element to project through it. Of course, in 80 practice, the parts are adjusted so that more of the wheel than simply an element extends through this opening. The wheel projects through just sufficiently to polish the flat 85 surface of a board or the like held against the work-rest. In this way the work-rest furnishes a support on both sides of the opening for the work, and the wheel will grind it down to a uniform flat surface, as 90 will be understood readily.

In addition to the work-rest itself, I provide a work-support in the form of a shelf or plate 28. This is carried by the work-rest at right-angles thereto and is secured to 95 it by screws 29 or the like. This can be adjusted up and down the surface of the work-rest so that an article resting on it and on the work-rest can be operated upon at any desired distance from the center of the 100 wheel. In this way, it will be understood that the surface speed of the portion of the wheel that operates on the work can be varied simply by varying the distance of the work-support 28 from the center of the 105 wheel and without changing the speed of rotation of the wheel. This is a convenient thing because it is easy for the workman to

get the maximum speed of operation without burning the work.

The wheel opening can be made by cutting out the opening 27 roughly and then putting 5 it up against the wheel and allowing the wheel to rotate and grind it to the proper shape, but if desired, the edges of this opening may be formed of two metal pieces 29 secured to the work-rest and conforming to 10 the shape of the rest of the same. It will be noted that these, as well as the adjacent surfaces, are concave on the back.

The wheel can be adjusted longitudinally in one direction by means of an adjusting 15 screw 30 engaging a fiber disk 31 at the end of the shaft 11. It does not have to be adjusted in the other direction because the work pressing on it will hold it back against this screw.

20 From this it will be seen that in this very simple manner a device is provided which affords an opportunity for varying the surface speed of the operation without operating any of the ordinary speed-changing devices; which provide for polishing the 25 work uniformly on the surface; and which is of a much more simple form than the devices for sanding now on the market.

Although I have shown and described 30 only a single form of the invention, I am aware of the fact that many modifications can be made therein by any person skilled in the art without departing from the scope of the invention as expressed in the claims. 35 Therefore I do not wish to be limited to all the details of construction herewith shown and described, but

What I do claim is:—

1. The combination with a sanding wheel 40 constituting a cone having an obtuse angle at the apex, of a flat work-rest having a segmental opening therethrough, through which the wheel projects.

2. The combination with a sanding wheel 45 constituting a cone having an obtuse angle at the apex, of a flat work-rest located substantially transverse to the axis of the wheel and tangent to the conical surface of the wheel, and having an opening through it 50 through which the wheel projects slightly.

3. The combination with a conical sanding wheel of a comparatively flat shape, of a flat work-rest located with its operative surface substantially tangent to the conical 55 surface of the wheel, and having a segmental opening through the same from the center of the wheel to its edge, whereby the wheel can project through the opening and have a surface thereof slightly beyond said operative surface and parallel therewith.

60 4. The combination with a conical sanding wheel, of a flat work-rest located substantially tangent to the conical surface of

the wheel and having an opening through it, through which the wheel projects 65 slightly, and a work-support on said work-rest, and adjustable thereon from the center to the edge of the wheel.

5. The combination with a conical sanding wheel, of a flat work-rest having a segmental opening therethrough, through which the wheel projects, and a work-support adjustable along said work-rest from the center to the edge of the wheel for varying the speed of the sanding surface on the 75 work.

6. The combination with a conical sanding wheel, of a flat work-rest having a segmental opening therethrough, through which the wheel projects, and a casing in which 80 said wheel is located, said work-rest constituting a wall of said casing and being removably connected with the remainder of the casing.

7. The combination of a casing having 85 two removable front plates, one at the bottom and the other at the top, the top plate being inclined and having an opening vertically arranged therethrough but wider at the top than at the bottom, a horizontal 90 shaft projecting into said casing, and a conical sanding wheel mounted on the end of said shaft in the casing and projecting through said opening.

8. The combination of a casing having 95 two removable front plates, one at the bottom and the other at the top, the top plate being inclined and having an opening vertically arranged, a horizontal shaft projecting into said casing, a conical sanding wheel mounted on the end of said shaft in the casing and projecting through said opening, a work-support mounted on the front of the inclined plate for receiving work thereon, 105 said work-support being adjustable up and down the plate for bringing the work into contact with surfaces of the sanding wheel running at different surface speeds.

9. The combination of a casing having 110 two removable front plates thereon, one at the bottom and the other at the top, the top plate being inclined and having an opening vertically arranged, a horizontal shaft projecting into said casing, a conical sanding wheel mounted on the end of said shaft in the casing and projecting through said opening, and means for adjusting said shaft toward said inclined plate.

In testimony whereof I have hereunto set my hand, in the presence of two subscribing 120 witnesses.

ALGERNON S. SPAULDING.
